INTERNAL COMBUSTION ENGINE

Filed Jan. 16, 1928

INVENTOR.

EDWARD E. NELDNER.

Raphae. mons.

ATTORNEY.

UNITED STATES PATENT OFFICE

EDWARD E. NEIDNER, OF MILWAUKEE, WISCONSIN

INTERNAL-COMBUSTION ENGINE

Application filed January 16, 1928. Serial No. 246,996.

This invention relates to internal combustion engines.

One object of the present invention is the provision in an internal combustion engine of improved power transmitting connections between the pistons and driven shaft by which each piston and connecting rod is caused to execute a simple harmonic rectilinear motion, to thereby eliminate the piston 10 side thrust and consequent unequal wear so common in commercial types of internal combustion engines, and to render more uniform the piston acceleration and deceleration in both halves of each piston stroke so as to 15 simplify the problem of counterbalancing and damping engine vibration.

The present invention may be utilized to particular advantage in internal combustion engines of the two cycle type since the rectilinear motion of the piston rods makes it possible to close the inner end of each cylinder to thus form a chamber for receiving, compressing and ultimately delivering the fuel charge to the combustion chamber.

Another object of the present invention is the provision in a two cycle internal combustion engine of means for equalizing the fuel charge within the cylinders.

Other objects and advantages will appear 30 from the following description of an illustrative embodiment of the present invention.

In the accompanying drawings:

Figure 1 is a sectional view of a two cycle internal combustion engine embodying the 35 present invention.

Fig. 2 is a fragmentary sectional view taken along the line 2-2 of Figure 1.

The engine selected for illustration is of the two cycle type and includes two pairs of 40 aligned cylinders 10-10' and 11-11', rigidly attached to and radially disposed about a substantially rectangular crank case 12. Each cylinder includes the usual water jacketed head 13 having a spark plug receiving opening 14. The inner end of each cylinder

is closed by a plate 15 whose edges are reduced, as indicated at 16, and firmly clamped between the end of the cylinder and the crank case. A piston 17, working in each cylinder, divides the interior thereof into a main compression and combustion chamber 18 and a pre-compression chamber 19. Each piston is fixed to the outer end of a piston rod 20 which extends through the pre-compression chamber 19 into the crank 50 case 12 and is closely fitted for lengthwise reciprocation in an appropriate bearing sleeve 21 carried by the plate 15.

The piston rods 20 of each pair of aligned cylinders are rigidly fixed at their inner ends 60 to the opposite sides of a yoke 22, so that the pistons, rods, and yoke of each pair of cylinders reciprocate as a unit. Each yoke is guided by and between a pair of rods 23, removably fixed in the crank case, and snugly 65 engaged within grooves 24 formed in the ends of the yoke. A crank shaft 25 journaled in the crank case is provided with a single crank pin 26 rotatably engaged within a pair of slide blocks 27 closely fitted for reciprocation 70 within appropriate guideways 28 formed in the respective yokes 22.

A combustible charge of fuel and air is admitted to each cylinder through the usual check controlled inlet 29 which communicates 75 with the pre-compression chamber 19 through a passage 30. Passage 30 also communicates with a port 31 formed in the wall of the main compression and combustion chamber 18. Communication between the passage 30 and the chambers 18 and 19 of each cylinder is controlled by the coating piston 17. In this instance each piston is provided with an apron 32 having a port 33 therein adapted to register with the lower end of passage 30, 80 when the piston reaches the inner end of its stroke, and to register with the port 31, when the piston reaches the outer end of its stroke. As the piston approaches the inner end of its stroke it also uncovers the port 31 to thereby 85 90

combination of a plurality of pairs of cylinders, a piston in each cylinder coacting therewith to form a combustion chamber, a chamber in each cylinder for receiving and forcing fuel into the combustion chamber therein, pressure responsive means associated with the receiving chambers of each pair of cylinders for opening communication therebetween, and means for adjusting said means to simultaneously and uniformly vary the maximum pressures in said receiving chambers.

In witness whereof, I hereunto subscribe my name this 12th day of January, 1928.

EDWARD E. NELDNER.
